UNITED STATES PATENT OFFICE.

NILS P. NYBERG, OF WAKEFIELD, NEBRASKA.

ADJUSTABLE TANGENTIAL DRIVING MECHANISM.

1,183,585.

Specification of Letters Patent. Patented May 16, 1916.

Application filed January 24, 1914. Serial No. 814,043.

To all whom it may concern:

Be it known that I, NILS P. NYBERG, a citizen of the United States, residing at Wakefield, in the county of Dixon and State 5 of Nebraska, have invented certain new and useful Improvements in Adjustable Tangential Driving Mechanism, of which the following is a specification.

My invention relates to adjustable tangential driving mechanism adapted to be used 10 particularly in connection with washing machines wherein the wringer is designed to be movable to different positions for the purpose of operating on clothing being 15 washed at different stages of their treatment.

With the above and other objects in view, the invention consists in the novel construction and arrangement of parts hereinafter 20 described, shown in the drawings and claimed, it being understood that changes falling within the scope of what is claimed 25 are contemplated.

In the drawing Figure 1 is a view of the 25 machine looking at the operator's side; Fig. 2 is a view of the opposite or driving side; Fig. 3 is a top view; Fig. 4 is a front elevation of the machine; and Fig. 5 is a vertical cross section taken centrally of the washing 30 machine.

The frame of this machine is of a longitudinal form and comprises the corner posts 1 which are connected longitudinally by means of the sill 2 at the front and the sill 35 3 at the rear of the machine. Transversely the frame is connected by the cross sills 4. At the top of the frame, and extending lengthwise thereof, are side strips 5 which are connected at each end by means of cross 40 pieces 6. Mounted on the frame at one end thereof, is a washing machine 7 which may be of any suitable construction, and has the lid 8 which is hinged as at 9 to be swung away from the top of the machine. Any 45 suitable mechanism is employed for operating the agitator or stirring device 10, and is mounted, as usual, on the top of the machine, the mechanism shown consisting of the yoke 11, which is mounted on the top 50 of the machine for sliding movement and a flexible cable or chain 12, which is connected to the ends of the yoke and wound about the spindle 13 at the top of the shaft 14 of the agitator 10 so that as the yoke 11 slides 55 it causes the spindle 13 and the agitator 10 to turn. A shaft 15 is journaled on the top 8

of the machine and at its inner end, adjacent the yoke 11, is provided with a disk 16, which has an eccentrically disposed pin 17 which engages a vertical slot 18 in an upstanding portion 19 of the yoke 11. As 60 is apparent, the rotation of the shaft 15 will cause the pin 17 to operate in the slot 18 and impart a reciprocal movement to the yoke 11, whereby the agitator 10 will be 65 caused to oscillate.

Extending lengthwise of the frame of the machine, at the rear thereof, and near the top, is an endless sprocket chain 20 which is driven by a sprocket wheel 21 on the main 70 or drive shaft 22 at the machine end of the frame. This shaft 22 is provided with a pulley 23 or other means whereby the shaft may be power driven. The chain 20 travels over a chain-guide throughout its entire 75 length, which chain-guide is constructed with a stationary part 24 adjacent the machine and a part 25 which is pivotally connected with the stationary part 24 and vertically movable to engage the chain with, 80 and disengage it from parts hereinafter described. The chain guide is provided at the end distant from the drive shaft 22 with an idler 26 which is connected with chain tightening means 27 whereby the chain may 85 be held at the proper tension. At this outer swinging end of the chain guide there is also provided a bracket 28 mounted on the frame, to confine the chain guide in its movement. The drive shaft 15 of the washing 90 machine is provided with a sprocket 29 which engages the chain 20 when the cover 8 of the machine is lowered to the operating position, and said sprocket is moved out of engagement therewith, when the cover of the 95 machine is raised.

Mounted upon the frame of the machine are two receptacles 30 and 31, the receptacle 30 being located next to the machine 7 and the receptacle 31 being located next to the 100 receptacle 30, it being the intention that the clothes, after being washed in the machine 7, shall be transferred to the rinse water in the receptacle 30 and from the receptacle 30 to the bluing water in the receptacle 31. 105

Ways are provided at each side of the receptacles 30 and 31 and at the top thereof for a frame 32 which is adapted to slide lengthwise of the frame to a position adjacent the machine 7, and to various positions 110 above the receptacles 30 and 31. This frame 32 supports a wringer 33 of any suitable

construction, which has a shaft 34 extending to the rear side of the frame and this shaft is provided with a sprocket 35 positioned above the chain 20 and adapted to be engaged by said chain when the carrier 25 is raised.

Pivottally mounted to the rear sill 3 of the frame, are levers 36 which extend to the front or operator side of the frame and are provided with pedals 37 conveniently located for operation of the wringer in its different operating positions. These levers have a flexible connection 38 with a bell crank 39 which is pivoted to the frame of the machine under the carrier 25, and this lever 39 has an arm 40 extending laterally therefrom and provided with a part which engages the under side of the carrier 25. The connection of both the levers 36 with the bell crank lever 39 is such that pressure on either of the pedals 37 will raise the carrier 25, and the weight of the carrier 25 on the arm 40, automatically returns the pedals to their original position.

Assuming that the shaft 22 is being driven, the chain 20 will be constantly driven, and said chain is normally in engagement with the sprocket 29 of the machine, and normally out of engagement with the sprocket 35. When the washing machine is to be rendered inoperative the top 8 thereof is swung upwardly on its hinges 9, which movement disengages the sprocket 29 from the chain 20 and discontinues the operation of the machine.

When the wringer is to be used it is shifted lengthwise of the frame to the desired position and pressure applied to either of the pedals 37 which pressure through the flexible connections 38, bell crank 39 and arm 40 thereof, elevates the chain carrier 25 and brings the chain 20 into operative engagement with the sprocket 35 of the wringer. The wringer continues in operation while pressure is applied to either of the pedals 37, and when the pressure is removed, the carrier 25 and chain are returned automatically to the lowered position out of engagement with the sprocket 35.

What I claim is:

1. In a mechanism of the class described, the combination of a support, a shaft journaled for rotation in said support, a supplemental support slidable bodily upon the main support for movement in a single fixed plane longitudinally of the main support, operating mechanism upon the supplemental support, a guideway at one side and extending the length of the main support, an idler element at the outer end of the guideway, a driven element carried in the guideway, and connected to be driven from the drive shaft at one end and supported upon the idler element at the outer end of the guideway, and means for adjust-

ing the guideway support for the driven element whereby the latter may be caused to engage and operate the operating mechanism on the supplemental support in any of the positions of adjustment.

2. In a mechanism of the class described, the combination of a suitable support, a frame carried by said support and adapted to slide bodily thereon, in a single fixed plane longitudinally of the support, bearings in said frame, a pair of horizontally disposed roller shafts, geared together and mounted in the bearings of said frame, an engageable element on one of said shafts, a power shaft mounted in the support, a guideway extending lengthwise of the support of the frame and comprising two sections, one fixed and the other swingable with relation to the fixed section, an idler element at the outer end of the swinging section of the guideway, a continuously driven element connected to be driven from the power shaft, the same being carried within and extending the length of the guideway, its outer end being supported upon the idler element at the outer end of said guideway, and means for swinging the movable section of the guideway to cause the driven element to be engaged with or disengaged, at will, from the engageable element on one of said roller shafts in any of the positions of adjustment of the slidable frame.

3. In a mechanism of the class described, the combination of a support, guideways on said support, a slidable frame upon said support connected with the guideways thereon in a relation that the former may be moved to different positions on said support, a drive shaft, operating mechanism upon the frame provided with an engageable element adapted to be engaged by a driven member, a guideway upon the support extending lengthwise thereof, and in the line of movement of the frame, the same being pivoted at one end to permit it to swing, a supporting element adjacent the free end of the guideway for supporting the driven member, an endless driven member carried in the guideway, and connected to be driven from the drive shaft and also supported upon the supporting element of the guideway, and means for swinging the guideway member to cause the driven member to be engaged or disengaged at will with the engageable element on the operating mechanism in any of the positions of adjustment of the slidable frame.

4. In a mechanism of the class described, in combination, a support, a drive shaft on said support, a guideway extending lengthwise of said support and pivoted thereto at the end adjacent said drive shaft, a support for a driven element at the outer or free end of said guideway, an endless driven element disposed in the guideway and con-

5 nected with the drive shaft to be driven therefrom, and with the supporting element at the outer end of said guideway, a frame mounted upon the support intermediate the drive shaft and the outer end of the guideway adapted to be moved upon the support lengthwise of the guideway to different positions of placement intermediate said drive shaft and the outer end of the guideway, 10 an operating mechanism upon the frame provided with an engageable member, and means for swinging the guideway

into positions to cause engagement or disengagement of the endless driven element with the engageable member on the operating mechanism in any of the positions of placement of said frame.

In testimony whereof I have affixed my signature in presence of two witnesses.

NILS P. NYBERG.
